UNITED STATES PATENT OFFICE.

JEAN MARIE ANATOLE GÉRARD, OF PARIS, FRANCE, ASSIGNOR TO LA SOCIÉTÉ L'INDUSTRIELLE, OF SAME PLACE.

ROTARY MOTOR.

SPECIFICATION forming part of Letters Patent No. 600,671, dated March 15, 1898.

Application filed July 19, 1897. Serial No. 645,087. (No model.)

To all whom it may concern:

Be it known that I, JEAN MARIE ANATOLE GÉRARD, engineer, a citizen of the Republic of France, residing at Paris, in the Republic of France, have invented certain new and useful Improvements in Rotary Motors, of which the following is a specification.

This invention relates to that class of rotary motors in which a smooth disk forming a piston revolves in the interior of a cylinder and acts on a crank of the main shaft fitting in the axis of this cylinder.

It has for its object to reduce the quantity of steam employed in these motors by furnishing a means for working with double and even triple expansion, if desired.

The invention consists in the arrangement of parts hereinafter described and claimed.

In the accompanying drawings, Figure 1 is a transverse vertical section of the motor on the line xx of Fig. 2; Fig. 2, a plan view with the parts in section on the line xx of Fig. 1 and with the movable parts removed. Figs. 3, 4, and 5 are detail views indicating various positions of the distributing-valves. Fig. 6 is a vertical section on the line yy of Fig. 7, showing a modification of the distributing parts. Fig. 7 is a plan view.

The machine shown in Figs. 1 and 2 is composed of two similar cylinders A A', separated by a partition, and there is arranged in each cylinder a disk piston B, mounted on a crank b of the motor-shaft a in such a way as to revolve and circle freely on the periphery of the cylinder. The two cranks are placed at one hundred and eighty degrees to one another on the shaft a, the latter passing through the ends of the two cylinders, which have a common discharge-pipe c. Each cylinder A communicates with a cylinder D, placed at right angles to it and closed at its upper end by a plate d, which has a semicylindrical oscillating valve E, serving to regulate the admission into the cylinder D of steam arriving by the pipe F. In the cylinder D there is arranged a piston or sliding block G, forming a tight-fitting partition or abutment capable of protruding into the cylinder A, and this piston is provided on its lower face with a second semicylindrical oscillating valve H, the lower face of which bears on the circling

disk piston B and forms a tight joint on this disk. The two valves E and H rest in opposite directions on their seats and are provided with arms e and h, connected by a pin f, 55 which is fixed on one arm but free to work in a groove or slot formed in the other arm or in other suitable manner. Finally, the movements of these arms are limited by stops g.

The working of this machine is as follows: 60 In the position indicated in Fig. 1 the valve H, resting on the disk B, assumes an inclined position and by the intermediary of arms h and e forces the valve E to incline itself in the other direction. In these positions the 65 orifice i of the lower valve is closed and the orifice j of the upper valve is opened and gives passage to the steam arriving by the pipe F, which steam forces the piston G downward and presses the valve H strongly on the 70 disk B. This pressure being inclined in the direction of the arrow acts on the crank b, and this motive action, which commences as soon as the center of the disk B comes to the right of the vertical, is continued until the 75 tangential point k of the disk reaches k'. In this position (shown in Fig. 3) the orifice j of the valve E is closed and shuts off all communication of the cylinder D with the boiler, and the orifice i of the valve H opens and allows the volume of steam contained in the cylinder D to penetrate into the cylinder A, where it acts by expansion on the disk piston B. When the point of contact of this disk B has reached k², Fig. 4, the orifice j is still 80 closed, and the orifice i remaining open the expansion of the steam continues to be produced until the point of contact of the revolving disk B reaches the discharge-orifice c. At this moment, when the discharge is effected, the two orifices i and j are closed, as shown in Fig. 5, which figure shows the position of the valves when the disk B is at the highest point of its course. The same actions are then reproduced periodically. It will therefore be seen that the cylinder D acts with full 85 pressure for a half-rotation of the disk piston and that the cylinder A acts by expansion during the second half-rotation of the said disk. It is evident that during the first half- 90 rotation of the disk, as the orifice i of the valve H remains closed, there will be pro- 95 100

duced in the right-hand half of the cylinder A a vacuum which would oppose a deleterious resistance to the movement of the disk. In order to avoid this drawback, a discharge *l* is arranged in the partition dividing the two expansion-cylinders A and A'; and the position of the disk placed behind this partition is indicated in dotted lines in Fig. 1 and shows that the cylinder A' contains at this moment steam which expands and which could freely pass then into the right-hand part of the cylinder A and thus act on the disk B during the second half of its rotation. Owing to the use of the passage or port *l* there is therefore produced an important increase in the volume devoted to the expansion of the steam and which may be considered as a double useful expansion of the motive steam, and it is evident that the same effects will be produced alternately in the two cylinders A and A', arranged back to back.

Instead of using two cylindrical valves E and H, the reciprocal movements of which are determined by the connection of their arms *e* and *h*, the arrangement shown in Figs. 6 and 7 of the accompanying drawings may be employed. In this arrangement the lower hollow valve H is not modified; but the upper one E is replaced by a valve *m*, provided with openings *n* on its periphery and which receives at given moments a slight rotary movement sufficient to open or to close the admission-openings *o*, arranged in its seat *d*. For this object the valve *m* is fixed on a spindle *p*, provided near its extremities with helicoidal cams *r* and *r'*, and the piston G is provided with a cross-piece *t*, having helicoidal cams *s* and *s'* at each side. These cams are arranged in such a way that when the piston G reaches the summit of its course the fixed cam *s* encounters the cam *r* of the spindle *p* and brings the openings *n* of the valve into register with the openings *o*, formed in its seat, which thus allows the steam to penetrate into the cylinder *d*. While the piston G is descending again, the opening remains open. (See Fig. 6.) When the piston G reaches the bottom of its course, the fixed cam *s'* encounters the cam *r'* of the spindle *p* and displaces the valve *m*, the solid parts of which close the openings *o*, interrupting all communication of the cylinder *d* with the boiler. This action is then reproduced at each revolution of the disk B. The play of

the cylindrical valve H not being modified it is evident that the mode of working of the motor remains the same as in the preceding case.

It is evident that I do not limit myself to the arrangements and parts hereinbefore described in order to insure the distribution of the steam in the machine, the said arrangements being capable of being varied without modifying the spirit on which it is based, and, similarly, I may employ more than two cylinders A, coupled one to the other, if I judge it necessary.

I declare that what I claim is—

1. In a compound rotary motor composed of a cylinder having a discharge-pipe and containing a revolving piston working by expansion, and of a second cylinder carrying the inlet-pipe and containing a piston having a rectilinear movement acting with full pressure and bearing directly on the periphery of the revolving piston: the combination with a semicylindrical oscillating valve H for regulating the admission into the first cylinder A, of a valve *m* revolute on its seat and having openings for regulating the admission into the second cylinder, the spindle of the said valve being provided at its extremities with helicoidal cams adapted to be alternately actuated at each end of the course of the piston G by similar cams on this piston, substantially as hereinbefore set forth.

2. The combination with a single motor-shaft, of two similar rotary compound motors coupled and acting successively by direct action on the said motor-shaft, each compound motor comprising an expansion-cylinder containing a revolving piston and which is separated from the adjacent cylinder by a partition having an opening placed near the point where the steam admission is effected and each expansion-cylinder communicating with a cylinder which is placed at right angles and has a reciprocating piston acting at full pressure during its descending stroke on the periphery of the revolving piston of the corresponding expansion-cylinder, substantially as hereinbefore described.

In testimony whereof I have signed my name to this specification in the presence of two subscribing witnesses.

JEAN MARIE ANATOLE GÉRARD.
